UNITED STATES PATENT OFFICE

MAUNSELL B. JACKSON AND KENNETH M. CLIPSHAM, OF TORONTO, ONTARIO, CANADA,
ASSIGNORS TO LEASIDE ENGINEERING COMPANY LIMITED, OF LEASIDE, CANADA

ENGINE STARTER

Application filed March 31, 1930. Serial No. 440,324.

This invention relates to starters for internal combustion engines of the type in which the starter pinion is moved manually into meshing engagement with the engine gear and more particularly to the type of starter disclosed in our co-pending application No. 399,845, filed October 15, 1929, in which a manually operable member is adapted to engage, seriatim, two oppositely directed cam faces whereby the pinion may be turned first in one direction of rotation and then in the other direction to bring it into meshing registration with the gear during one continuous movement of the member. The cam faces are formed on a sleeve which is connected with the pinion by means of a clutch adapted to permit slippage between the sleeve and pinion whereby the member may complete its engagement with the first cam face to engage the second or reverse cam face should the first turning movement of the pinion be checked. This construction necessitates a large turning component of the force exerted by the member against the cam faces to tend to turn the sleeve and therefore only a correspondingly small axial component is provided to tend to move the sleeve axially. It is therefore necessary to provide separate means for presenting the pinion to the gear to ensure meshing of the pinion therewith.

The object of the present invention is to provide a starter of this type in which the above objectionable features have been eliminated and the construction has been simplified and strengthened.

We attain our objects by means of the constructions briefly described as follows. A slidable and rotatable outer sleeve, disposed on the armature shaft of the starter motor and telescoped on an inner sleeve, has pin and inclined slot connections with the inner sleeve. The latter has a disengageable drive connection with the starter pinion. Normally a spring holds the sleeves in their extended positions with the pins engaging the inner ends of their respective slots. The outer sleeve is provided with two steeply inclined faces which diverge in opposite directions from the axis of the sleeve to form an obtuse angled corner between them. One of these

faces is steeper than the other and a pin on a manually operable lever is adapted to engage the steeper face to shift the sleeves, spring and pinion as a unit towards the engine gear and under certain conditions, into mesh therewith. Should the pinion teeth collide with those of the gear the axial movement of the pinion and inner sleeve will be stopped and the continued pressure of the pin on the steeper face will compress the spring and shift the outer sleeve relative to the inner sleeve. The pin and inclined slot connections will thus cause one sleeve to rotate relative to the other whereby the pinion will be turned in one direction of rotation relative to the outer sleeve, or the latter will be turned in the opposite direction of rotation relative to the pinion. The reaction caused by the spring between the pin on the lever and the steeper inclined face tends to resist the turning of the outer sleeve relative to the pinion so that the latter will tend to turn rather than the sleeve.

If the turning of the pinion by the pin and inclined slot connections be checked the above mentioned resistance will be overcome and the sleeve will be turned relative to the pinion to move the obtuse angled corner past the pin on the lever so that this pin will engage the other inclined face.

The continued movement of the pin along the last mentioned face will cause a continuation of the reverse movement of the pinion. When the latter clears the gear, the spring will be free to enter the pinion into meshing relationship with the gear.

The constructions are hereinafter more fully described and are illustrated in the accompanying drawings in which

Fig. 1 is a longitudinal section, partly in side elevation, of our starter showing the parts thereof in their normal or inoperative positions;

Fig. 2 a diagrammatic view showing a development of part of the sleeves and illustrating the relative positions thereof when abutment between the pinion and gear teeth occurs;

Fig. 3 a view similar to Fig. 2 showing

the relative positions of the parts when the pinion has been turned to clear the gear;

5 Fig. 4 a view similar to Fig. 2 showing the relative positions of the sleeves and pinion when a corner jam occurs;

10 Fig. 5 a view similar to Fig. 4 showing the outer sleeve turned to reverse the direction of rotation of the pinion to relieve the corner jam;

15 Fig. 6 a view showing the positions of the parts when the pinion has been partly meshed by the spring after the corner jam has been relieved; and

20 Fig. 7 a diagrammatic view showing the pinion fully meshed and the spring slightly compressed when the lever closes the switch.

25 1 is a motor provided with an armature shaft 2 on which may be threaded a pinion 4 which is adapted to be shifted axially into and out of mesh with a gear 5 of the engine to be started. On the shaft is disposed a rotatable and slideable member or outer sleeve 6 which has pin and inclined slot connections 7 with an inner sleeve 8. The inner sleeve 8 is provided with clutch teeth 9 adapted to form a disengageable drive connection with similarly shaped teeth 10 on the pinion and which may be formed on the ends of the 30 teeth of the latter. The outer sleeve 6 is adapted to slide over the pinion clutch teeth 10 and is provided with a rigidly attached bearing 11 which is slideable on the shaft 2 to support the inner end of the sleeve. The 35 outer end of the outer sleeve is supported by a bearing 12 which is slideable on the shaft 2 and engages the inner end of the inner sleeve 8. A spring 13 engaging the bearings 11 and 12 tends to maintain the inner ends of 40 the inclined slots 7^a in engagement with the pins 7^b of the pin and slot connections 7.

45 The outer sleeve 6 has a substantially U-shaped cam slot 14 having faces 15, 16, 17, 18, a recess 19, and a corner 20. A pin 21 on a manually operable lever 22 initially engages the recess 19 to position the face 15 for engagement by the pin when the lever is operated. The face 15 is inclined to the axis of the sleeve 6 in the same direction of inclination as the slots 7^a but at a much steeper angle to the axis than the angle of the slots 7^a. The face 16 is inclined to the axis of the sleeve in the opposite direction of inclination to the face 15 and intersects the latter to form the obtuse angled corner 20. While the face 16 is also steeply inclined relative to the inclination of the slots 7^a it is not so steep as the face 15. Both the faces 15 and 16 are inclined at "pushing" angles rather than 50 "turning" angles while the slots 7^a are inclined at a "turning" angle rather than a "pushing" angle.

55 Assuming the parts are positioned as illustrated in Fig. 1 with the pin 21 held 60 by the usual spring 23 in the recess 19, the

mode of operation is as follows: The upper end of the lever 22 is moved by any suitable means to the left to move the pin 21 to the right and into engagement with the steeply inclined face 15 whereby the outer sleeve 6, 30 spring 13, and inner sleeve 8 will be moved as a unit to engage the teeth 9 with the teeth 10 on the pinion 4. The latter will thus be moved towards the gear 5 and, if the pinion teeth happen to be in alinement with the spaces between the gear teeth when the pinion reaches the gear, the continued axial movement of the sleeve 6 will move the pinion into engagement with an abutment 24. The starter motor 1 will be energized and the sleeves and pinion returned to their initial positions as hereinafter described.

35 If the pinion teeth collide with the gear teeth the axial movement of the inner sleeve 8 and the pinion 4 will be stopped, see Figs. 2 and 4. The continued movement of the lever will cause the pin 21 to press against the face 15 and move the outer sleeve 6, against the compression of the spring 13, relative to the inner sleeve 8 and the pinion 4. The pins 7^b 40 are thus moved along their slots 7^a to turn the inner and outer sleeves 8 and 6 relative to one another. The compressed spring 13 causes the steeply inclined face 15 to re-act against the pin 21 to tend to prevent the outer sleeve 6 from turning relative to the inner sleeve 8 so that the latter and thus the pinion 4 will tend to turn rather than the outer sleeve 6 (see Fig. 3). Immediately the pinion teeth clear the gear teeth the spring 13 is free to 45 expand to its initial position and mesh the pinion with the gear. The continued movement of the pin 21 against the face 15 will 50 move the pinion into engagement with the abutment 24.

55 Should this turning movement of the pinion be checked, as for example by a corner jam of the teeth of the pinion and gear, the corresponding turning movement of the inner sleeve 8 will also be checked. The pins 7^b 60 will therefore travel down the slots 7^a and turn the outer sleeve 6, against the reaction of the face 15 and pin 21, in a direction of rotation opposite that imparted by the said pin and slot connections 7 to the inner sleeve 8 and pinion 4. The sleeve 6 is thus turned relative to the pinion to move the face 15 out of engagement with the pin 21 and the corner 20 past the pin so that the latter now engages the face 16, see Fig. 5. This turning movement of the sleeve 6 will be continued by the continued pressure of the pin 21 against the face 16 which will result in the sleeves 6, 8 and pinion 4 being turned as a unit in a reverse direction of rotation. When the pinion teeth clear the gear teeth, the spring 13 65 will move the pinion into meshing relationship with the gear and the continued movement of the pin against the face 16 will move 70 the sleeves and pinion 4 into their initial positions as hereinafter described.

the pinion into engagement with the abutment 24.

As hereinbefore described the angle of the face 16 is a "pushing" angle rather than a "turning" angle but as this face is not so steep as the face 15, the pin 21 co-acts with the face 16 to tend to turn the sleeve instead of tending to prevent it from turning as in the case of the re-action between the face 15 and the pin. The turning component of the force exerted by the pin 21 against either of the faces 15, 16 is small in comparison with the component tending to move the sleeve 6 axially and never becomes sufficiently great to cause the clutch teeth 9, 10 to ride over one another. Therefore the inner sleeve 8 and pinion 4, while pressed against one another by means of pin 21, face 15 or 16, spring 13 and gear 5, will be turned as if they were one piece. Any rotary or axial movement of the outer sleeve 6 relative to the inner sleeve 8 will thus be relative to the pinion 4.

After entrance of the pinion has been effected and meshing thereof has been completed, by the spring 13 and/or the pin 21, with the pinion in engagement with the abutment 24 (see Fig. 7), the movement of the lever 22 may be continued against the compression of the spring 13 to close a switch 25 for energizing the motor 1. During the last mentioned movement of the lever 22 the pin 21 may be engaged with either the face 15 or 16 depending on whether the entrance of the pinion took place without any, or during its initial, turning movement or during its reverse turning movement respectively. But wherever the pin 21 be found when the starter motor is energized to rotate the shaft 2 in a clockwise direction of rotation and thus the pinion 4, clutch teeth 9 and 10, inner sleeve 8, pin and slot connections 7 and outer sleeve 6, the pin 21 will under normal starting conditions travel over the face 16 and face 15 or the face 15 alone, as the case may be, and will engage the face 17 to return the sleeve 6 to its initial position against a brake washer 26. The inner sleeve 8 is moved back by the pin and slot connections 7 with the outer sleeve 6. As hereinbefore mentioned the spring 13 is compressed before the switch 25 is closed so that the expansion of the spring will initiate the return movement of the outer sleeve as soon as the faces 15, 16 are turned out of engagement with the pin 21 and the friction of the bearing 11 on the shaft 2 will assist in turning the sleeve to worm it along the pin 21.

When the engine starts the pinion will be automatically demeshed by its threaded connection 2^a with the shaft 2 and this demeshing movement of the pinion is limited by a stop collar 27 so that the clutch teeth 9 and 10 are normally spaced apart to permit relative rotation thereof until the operator releases the lever 22 from the switch 25. The

spring 23 will then actuate the lever to move the pin 21 along the cam face 17 until the pin engages the recess 19 which positions the sleeve 6 so that the pin will engage the face 15 when the lever 22 is again actuated to start the engine.

If the pinion should be presented to the gear while the latter is rotating in its normal direction of rotation, the pinion 4 and thus the sleeves 6 and 8 will be turned by the gear 5 in a forward direction of rotation so that the return cam face 17 will be moved into engagement with the pin to return the sleeves to their initial position and thus remove the pressure tending to force the pinion against the gear.

The parts are prevented from being damaged, if the pinion be presented to the gear while it is moving in a backward direction of rotation, by the leg 14^a of the slot 14 which provides clearance for the pin 21. Should the operator continue the movement of the lever 22 until it closes the switch 25, the shaft 2 will be rotated to drive the pinion 4 and thus rotate the sleeves 6 and 8 in a forward direction whereby the face 18 on the wall of the slot leg 14^a will engage the pin 21 to return the sleeves.

In case the shaft 2 is still running when lever 22 is actuated, the sleeves 6 and 8 will turn with the pinion 4 to bring the return face 17 into engagement with the pin 21 whereby the sleeves will be returned to their normal position without pushing the pinion against the gear.

While the pinion is shown and described as initially turning in a forward direction of rotation that is to say in its direction of rotation while driving the gear, it is obvious that the direction of inclination of the slots 7^a and the faces 15 and 16 could be each reversed so that the pinion would be turned backward initially.

It is also obvious that any means such as a straight spline or overrunning clutch may be substituted for the helical spline 2^a to drive the pinion 4 from the shaft 2. As this invention relates chiefly to the mechanism for entering the pinion the latter may be withdrawn from the gear by any suitable well known means between the sleeve 6 and the pinion 4 instead of the well known automatic ejecting means shown and described herein.

What we claim as our invention is:

1. An engine starter including a rotatable shaft; means for connecting the shaft with the gear of an engine to be started comprising a pinion movable into mesh with the gear; and a manually operable device for moving the pinion into mesh with the gear, the said device including provisions which operate in case the pinion collides with the gear to produce relative rotation of said pinion and device, the said device also including provisions, which are conditioned for operation

by the relative rotary movement of the device and pinion in case the pinion fails to mesh during the said relative movement, to produce a rotary movement of the pinion into meshing registration with the engine gear while the pinion is being pressed against the engine gear.

2. An engine starter including a rotatable shaft having a starter pinion mounted thereon for longitudinal movement thereof to mesh with a gear of an engine to be started; a member slideable and rotatable on the shaft and having a drive connection with the pinion, the member being provided with two inclined faces; means for engaging one face to move the pinion axially; and means for moving the member and engaging means relative to one another whereby the engaging means may engage the other face in case of gear tooth abutment.

3. In a mechanism for connecting a rotatable device with a gear, the combination with a pinion adapted to be shifted into engagement with the gear, of a rotatable and slideable member having a driving connection with the pinion; and a manually operable member, the rotatable member having provisions for engagement by the manual member to push the pinion towards the gear and having separate provisions for engagement by the manual member to turn the pinion, the said rotatable member also including provisions for positioning the second mentioned provisions for engagement by the manual member in case of gear tooth abutment.

4. In a mechanism for connecting a rotatable device with a gear, the combination with a pinion adapted to be shifted into engagement with the gear, of a rotatable and slideable member having a driving connection with the pinion; a manually operable member, the rotatable member having provisions for engagement by the manual member to push the pinion towards the gear and having separate provisions for engagement by the manual member to turn the pinion, and means for rotating the pinion and rotatable member relative to one another in case of gear tooth abutment whereby the second mentioned provisions will be positioned for engagement by the manual member if the pinion teeth fail to clear the gear teeth.

5. In a mechanism for connecting a rotatable device with a gear, the combination with a pinion adapted to be shifted into engagement with the gear, of an outer sleeve having two inclined faces, an inner sleeve having an inclined plane connection with the outer sleeve and a drive connection with the pinion; and a manually operable member adapted to engage one face to move the pinion into mesh with the gear and to move the outer sleeve relative to the inner sleeve in case of gear tooth abutment whereby the

pinion and outer sleeve will turn relative to one another to position the other face for engagement by the member if the pinion is still abutting the gear.

6. In a mechanism for connecting a rotatable device with a gear, the combination with a pinion adapted to be shifted into engagement with the gear, of an outer sleeve having a face steeply inclined in one direction to the axis of the sleeve and having another face inclined in the opposite direction to that of the first face to form an obtuse angled corner between them; an inner sleeve having an inclined plane connection with the outer sleeve and a drive connection with the pinion; and a manually operable member adapted to engage the first mentioned face to move the pinion into mesh with the gear and to move the outer sleeve relative to the inner sleeve in case of gear tooth abutment whereby the pinion and outer sleeve will turn relative to one another to position the corner past the member so that the latter will engage the second mentioned face to reverse the direction of rotation of the pinion if its first turning movement be obstructed.

7. An engine starter including a rotatable shaft; a pinion threaded thereon and shiftable into engagement with a gear of an engine to be started; an outer sleeve having two faces; an inner sleeve having a pin and inclined slot connection with the outer sleeve and a drive connection with the pinion; a spring tending to extend the inner sleeve relative to the outer sleeve; and a manually operable member adapted to engage one of the faces to move the pinion into mesh with the gear and to move the outer sleeve relative to the inner sleeve in case of gear tooth abutment whereby the pinion and outer sleeve will turn relative to one another to position the other face for engagement by the member if the pinion is still abutting the gear.

8. An engine starter including a motor having an extended shaft; a pinion threaded thereon and shiftable into engagement with a gear of an engine to be started; an outer sleeve having a substantially U-shaped slot having one leg inclined to the axis of the sleeve, the portion of the slot between the legs thereof forming two intersecting faces; an inner sleeve having a pin and inclined slot connection with the outer sleeve and a drive connection with the pinion; a spring tending to extend the sleeves relative to one another; a switch for controlling the supply of energy to the motor; and a manually operable member adapted to engage one of the faces to move the pinion into mesh with the gear and to move the outer sleeve relative to the inner sleeve against the compression of the spring in case of gear tooth abutment whereby the pinion and outer sleeve will turn relative to one another to clear the pinion

teeth or to position the other face for engagement by the member if the pinion is still abutting the gear, the manually operable member also being adapted to close the switch to energize the motor, the other leg of the U-shaped slot being adapted to free the manual member should the pinion contact with the gear while it is moving in a backward direction and the said inclined leg of the slot being adapted to engage the manual member to return the sleeves to their initial positions when the motor is energized.

9. An engine starter including a rotatable shaft having a starter pinion mounted thereon for longitudinal movement thereof to mesh with a gear of an engine to be started; a manually operable member; a slideable and rotatable sleeve having a face adapted to be engaged by the member to move the sleeve axially; an inclined face on the sleeve adapted to be engaged by the member to turn it in one direction of rotation; and means interposed between the sleeve and the pinion for changing an axial movement of the sleeve into a relative rotary movement of the pinion and sleeve in case of gear tooth abutment whereby the pinion may be turned in one direction of rotation to clear its teeth or the sleeve may be turned to bring the inclined face into engagement with the member to turn the pinion in the opposite direction of rotation.

10. An engine starter including a rotatable shaft having a starter pinion mounted thereon for longitudinal movement thereof to mesh with a gear of an engine to be started; a manually operable member; a slideable and rotatable sleeve having an inclined face adapted to be engaged by the member to move the sleeve axially; a second inclined face on the sleeve adapted to be engaged by the member to turn it in one direction of rotation; and means interposed between the sleeve and the pinion and having a disengageable driving connection with the latter for changing an axial movement of the sleeve into a relative rotary movement of the pinion and sleeve in case of gear tooth abutment whereby the second face will be moved into engagement with the member if the pinion fails to clear its teeth.

11. An engine starter including a rotatable shaft having a starter pinion mounted thereon for longitudinal movement thereof to mesh with a gear of an engine to be started; a member slideable and rotatable on the shaft and having a drive connection with the pinion, the member having a face steeply inclined in one direction to the axis of the sleeve and having another face inclined in the opposite direction to that of the first face to form an obtuse angled corner between them; means for engaging the first mentioned face to move the pinion into mesh with the gear; and means for moving the member and en-

gaging means relative to one another whereby the engaging means may engage the second mentioned face in case of gear tooth abutment.

Signed at the city of Toronto, Canada, this 27th day of March 1930.
